OF D 18,646

DESIGN.

UHLMANN & J. PETERS.

DRESS TRIMMING.

No. 18,646.

Patented Oct. 2, 1888.

UNITED STATES PATENT OFFICE.

GEORG BUHLMANN AND JULIUS PETERS, OF BERLIN, GERMANY, ASSIGNORS
TO DIECKERHOFF, RAFFLOER & CO., OF NEW YORK, N. Y.

DESIGN FOR DRESS-TRIMMINGS.

SPECIFICATION forming part of Design No. 18,646, dated October 2, 1888.

Application filed August 3, 1888. Serial No. 281,892. Term of patent 3½ years. Patented in Germany May 15, 1888, Nos. 3,763 and 3,764, and in Austria-Hungary June 7, 1888, No. 28,961 and No. 28,962.

To all whom it may concern:

Be it known that we, GEORG BUHLMANN and JULIUS PETERS, subjects of the King of Prussia, Emperor of Germany, residing at Berlin, Prussia, Germany, have invented a new and original Design for Dress-Trimmings, (for which we have obtained patents in the German Empire, Nos. 3,763 and 3,764, dated May 15, 1888, and in Austria-Hungary, No. 28,961 and No. 28,962, dated June 7, 1888,) of which the following is a specification, reference being had to the accompanying photograph, which forms a part of the same.

The invention relates to a design for the arrangement of the cords or braids in dress-trimmings; and it consists in a novel configuration and combination of these cords or braids.

The accompanying photograph is a face view of my design.

The design consists of two parts—the facing and the backing. The facing consists of a series of braids or cords, *a*, each of which is ar-

ranged in an undulating or wavy line, which passes alternately to the right and left of a straight central line. This facing appears 25 above—that is, as lying upon a backing composed of a series of braids or cords, each arranged in an undulating or wavy line, as shown, but so that the greater portion of these cords or braids is visible from above the surface, and so that the underlying series, *b b*, as a whole, presents the appearance of transverse cords substantially parallel with each other and traversing the fabric from side to side. 30

What we claim as new, and desire to secure 35 by Letters Patent, is—

The design for dress-trimmings, consisting of the design substantially as shown.

GEORG BUHLMANN.
JULIUS PETERS.
